UNITED STATES PATENT OFFICE.

HENRY W. SIEVER, OF DANVILLE, ILLINOIS.

HEATING STOVE.

Application filed December 31, 1921. Serial No. 526,168.

To all whom it may concern:

Be it known that I, HENRY W. SIEVER, a citizen of the United States, and a resident of Danville, in the county of Vermilion and State of Illinois, have invented certain new and useful Improvements in Heating Stoves, of which the following is a specification.

My invention relates to heating stoves, and it consists in the combinations, constructions and arrangements herein described and claimed.

An object of my invention is to provide a heating stove of simple construction which is provided with means for conducting air to the combustion chamber to mingle with the combustible gases therein, whereby such gases are consumed within the stove and a great economy thus effected in that practically all the combustible elements in a fuel charge are utilized in the generation of heat.

A further object of my invention is to provide in a stove of the character described, a novel means for causing the induction of cold air from the upper end of the stove to the firebox and for deflecting the ascending heated current radially, thereby occasioning the radiation of a maximum amount of the heat generated in the stove.

Other objects and advantages will be apparent from the following description and the novel features of the invention will be particularly outlined in the appended claims.

My invention is illustrated in the accompanying drawing, forming a part of this application, in which:

Fig. 1 is a view, mainly sectional, and partly in side elevation, of a stove embodying the invention,

Fig. 2 is a section along the line 2—2 of Fig. 1, and

Fig. 3 is a section along the line 3—3 of Fig. 1.

Referring now to the drawing, the numeral 1 denotes a substantially cylindrical body or drum mounted upon a fire pot 2, which latter has an ash pit portion 3 supported upon legs 4. The body or drum 1 has an upper end 5 provided with an opening 6 adjacent to one edge thereof, to which a smoke pipe or flue 7 is joined.

The upper end 5 is provided also with a central opening into which fits the upper

end of a frusto-conical member 8. The latter has a length substantially the same as that of the body or drum 1 and is provided with an integral outwardly extending annular flange 9 at its lower end, which flange is of sufficient size diametrically to closely interfit the body or drum 1, whereby a substantially airtight joint is provided between the flange and the inner wall of the body or drum 1.

The frusto-conical member 8 is provided with an upper end 10 having a plurality of openings 11 formed therein and a rotary register valve 12 having a plurality of openings 13 therethrough is mounted upon the end 10. The number and arrangement of openings 13 are respectively the same as the number and arrangement of the openings 11 and each of the openings 13 has the same area as each of the openings 11, whereby the register valve 12 may be rotated as desired to vary the volume of air permitted to enter the frusto-conical member 8 at the upper end thereof.

A plurality of spaced openings 14 are formed through the flange 9. The fire pot 2 has an inclined inlet 15 located below the plane of the flange 9 and normally closed at its outer end by a hingedly attached fuel door 16 which is imperforate and is normally maintained in closed position, as illustrated, by the influence of gravity. A grate 17 is positioned within the fire pot 2 at the lower end thereof.

From the foregoing description of the various parts of the device, the operation thereof may be readily understood. A quantity of fuel to be burnt is fed through the inlet 15 and rests upon the grate. A door or damper 18 in the ash pit 3 is opened and the fuel resting upon the grate is ignited. After a short interval, the door or damper 18 is closed and remains closed thereafter. The register valve 12 is turned to admit a desired volume of cold air at the upper end of the frusto-conical member 8. The cold air will pass downward within the frusto-conical member 8, as indicated by the arrows in Fig. 1, and upon entering the fire pot 2 will mingle with the gases therein, which gases may be practically completely consumed when mixed with the admitted air. Ordinarily, such gases pass directly to the upper part of the body or drum and thence through the flue 7 without being consumed, thereby causing a considerable waste.

The heated currents, comprising the products of combustion, are deflected outwardly by the admitted currents of colder air and by the flange 9. Such heated currents pass 5 through the openings 14 and then pass upward close to the inner wall of the body or drum 1, thereby insuring the radiation of practically all the heat generated. I have found in practice that the best results are 10 obtained when the respective openings 11, 13, and 9 are formed in such manner that the aggregate area of each set of openings is the same as that of every other set of openings and the same as the area of the 15 ingress end of the flue 7. However, good results may be obtained when the aggregate areas of the respective sets of openings vary from the proportion stated.

Obviously my invention is susceptible of 20 embodiment in forms varying in detail from that illustrated and described in the accompanying drawing and in the foregoing description, and I therefore consider as my own, all such modifications and adaptations 25 of the form of the device illustrated and described which properly fall within the scope of the invention as outlined in the appended claims.

I claim:—

30 1. A stove comprising a fire pot, a substantially cylindrical stove body mounted

thereon and being provided with an upper end, said upper end having a central opening for the admission of cold air and an outlet located adjacent to one edge thereof, 35 a frusto-conical member having the smaller end thereof received within the said central opening and being provided with an end having openings therethrough, said frusto-conical member having a length substantially equal to that of the stove body and being formed with an outwardly extending annular flange at its lower end closely fitting within the stove body, said flange having a plurality of spaced openings therethrough, and a valve for controlling the openings through the end of the frusto-conical member. 40

2. In a stove, a frusto-conical deflecting member having an outwardly extending flange at its larger end and being provided 50 with a closure at its other end, said flange having a plurality of spaced openings therethrough and said closure being formed with a plurality of openings therethrough, the 55 aggregate area of the openings through said flange being substantially the same as the aggregate area of the openings through said closure, and means for controlling the openings through the closure.

HENRY W. SIEVER.
